UNITED STATES PATENT OFFICE

NELS H. NELSON, OF ELBOW LAKE, MINNESOTA

METAL LATH

Application filed June 24, 1930. Serial No. 463,449.

This invention relates to a metal lath such as used in building construction work. Metal laths of the ordinary types when assembled generally lap at their corners, making four thicknesses at these points. These excessive thicknesses are objectionable because it is frequently difficult to properly coat thelapping portions of the laths with plaster and produce a smooth finish.

It is an object of the present invention to provide a metal lath having means whereby when a number of laths are assembled they can be placed edge to edge without producing an objectionably thick lap at every corner.

Another object is to provide a lath with means for engaging the next adjoining laths so that all of them will be properly held together.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings

Figure 1 is a plan view of the lath, a portion being broken away.

Figure 2 is an elevation of one side thereof.

Figure 3 is an elevation of the opposite side.

Figure 4 is a view partly in elevation and partly in section, showing the edge portions of three laths assembled, each of the laths being broken away.

Figure 5 is a view on a reduced scale showing three laths positioned in close proximity to each other prior to being joined.

Referring to the figures by characters of reference, 1 designates a lath which can be formed of a sheet of metal with slots cut into it, as shown, or can be made of expanded metal. Formed in the plate adjacent to and parallel with one side edge is a V-shaped rib 2 providing a corresponding channel 3, and

formed adjacent to and parallel with one end edge of the plate is another V-shaped rib 4 providing a corresponding channel 5. The outer walls of the channels 3 and 5 are formed with longitudinal slots 6, any desired number 55 of these being used and they being of any preferred length. The other side and end edges of the lath have projecting tongues 7 slightly offset as indicated at 8.

In practice the laths are assembled edge to 60 edge and when so located the tongues 7 will project under the adjacent edge portions of the next adjoining laths and will extend into the slots 6. Thus the laths will abut at their meeting edges and they can be placed in any 65 desired relation to each other without producing any bulky laps.

What is claimed is:

Sheet-metal laths abutting at their adjoining edges and having their corresponding 70 faces flush, there being ribs adjacent to two edges of each lath and diverging from one of the corners thereof, and tongues extending from the other edges of each lath, each of the ribs having openings into which the tongues 75 of the adjoining laths project.

In testimony that I claim the foregoing as my own, I have hereto affixed my signature.

NELS H. NELSON.
